DICTATING MACHINE

Leland D. Norton, Bridgeport, Conn., assignor to
 Dietaphone Corporation, New York, N. Y., a
 corporation of New York

Application October 5, 1936, Serial No. 103,960

8 Claims. (Cl. 179—100.4)

The present invention relates to an improvement in dictating machines. One object thereof has been to provide apparatus which presents more flexible adaptability to dictating voices of different volumes or having different tonal or other properties or qualities. A further object has been to provide a dictating machine of the universal type, i. e., for recording and reproducing, which may combine satisfactory or accepted general features of construction of known types of acoustical machines with novel features affording certain advantages inherent in electrical over purely mechanical recording and transmitting.

Having in view the foregoing and other objects and advantages, the present invention may be considered, in some respects, an improvement over the type of dictating machine of which one form is illustrated and described in Patent No. 1,989,783, to which reference is made for a clearer understanding of the purpose and scope of the improvements here considered.

One embodiment of my invention is illustrated in the drawings appended hereto and in which—

Figure 1 is an end elevation with parts shown in cross section;

Figure 2, a detail illustrating one form of change over switch suitable for the purposes of the present invention;

Figure 3, a transverse section on the line 3—3 of Figure 2;

Figure 4, a diagrammatic view showing the functional relationship of parts of the apparatus illustrated in Figure 1;

Figure 5, an enlarged detail in longitudinal section of the electric recorder-reproducer unit and mounting therefor;

Figure 6, a section on the line 6—6 of Figure 5; and

Figure 7, a wiring diagram.

The apparatus shown in the drawings includes conventional mechanisms (a) for holding and controlling rotation of the record cylinder upon which the dictation is to be recorded; (b) for automatically moving the electric recorder-reproducer unit and stylus carrier longitudinally thereof during recording and reproducing; and (c) for manually moving the recorder-reproducer unit and stylus carrier transversely thereof, i. e., to and from their recording, neutral, and reproducing positions, respectively.

The drawings also illustrate more particularly mechanisms according to my invention for electrical recording and reproducing and for shifting

readily from recording to reproducing and vice versa or to neutral.

Referring to Figure 1, the record cylinder 1 is removably mounted in a well known manner on a mandrel 2 driven by shaft 3 having a clutch connection with a driving pulley 4 which is actuated by a belt, not shown, from the motor 5, Figure 7. A switch 6 closes the motor circuit when the mouth piece 7 is removed from its supporting hook 8. A tension spring 9, Figure 1, 10 tends to yieldingly retain switch 6 in circuit closing position. For this purpose, said spring has one end attached to the frame of the machine and its other end to the link 10 which operatively connects hook 8 with switch 6 through 15 arm 11.

With motor 5 in operation, shaft 3 and consequently mandrel 2 are operated at will by a clutch interposed between the motor and said shaft. As shown in Figure 4, one suitable form 20 of clutch for this purpose includes a yoke 12 supported on a compound rocking lever pivotally mounted on a shaft 13. A spring 14 attached to an arm 15 of said lever tends to deflect yoke 12 in a direction to disengage a clutch member 3' 25 carried by shaft 3 from the toothed hub 16 of pulley 4.

Yoke 12 is rocked at will by the operator in clutch engaging direction against pull of spring 14 by a bell crank lever 17 pivotally mounted to 30 engage an arm 18 of the compound lever which carries yoke 12, and is actuated by the Bowden wire 19 from button 20 mounted conveniently to the mouth piece 7, it being understood that in this embodiment, the wire 19 extends through 35 flexible tube 21. Thus, by pressing down on button 20, the operator causes mandrel shaft 3 to engage with the pulley 4 to rotate the record cylinder holding mandrel 2. When pressure on button 20 is released, the clutch is disengaged 40 and mandrel 2 stops rotating.

In adapting a dictating machine having the known features as above described for electrical recording and reproducing according to the invention forming the subject matter of this application, I employ, in one embodiment, a recorder-reproducer unit mounting having certain features of construction like those of the sound box mounting described and shown in Patent No. 1,606,744 and illustrated in a form suitable for 50 present purposes in Figures 1, 5 and 6.

As shown in Figure 1, a recorder-reproducer unit casing 22 and a stylus arm 23 are mounted in conventional manner on carriage 24 for combined transverse and up and down or toward and 55

away movement in relation to the periphery of record cylinder 1 operatively positioned on mandrel 2. Carriage 24 travels longitudinally of said cylinder upon an upper carriage rod 25 and a lower carriage rod 26. A manually operated control lever 27 mounted on carriage 24 is actuated by the operator to move the casing 22 to and from its recording, neutral and reproducing positions, respectively; to engage carriage 24 with the feed screw 28 by means of a nut 29 when the casing is in its recording and reproducing positions; and to disengage said carriage from said feed screw while the casing is in neutral position, all in accordance with well known practice involving similar operation of a sound box and the stylus connected therewith.

Referring to Figures 1 and 5, a casing 43, mounted on carriage 24, supports a sliding sleeve 44 provided with an upper longitudinal slot 45 engaged by a guide pin 46. A lower longitudinal slot 47 accommodates an adjustable guide plate 48 secured in position on the casing 43 by a screw 49. An inner sleeve 50 is pivotally supported on the sliding sleeve 44 by screw studs 51 bearing in holes 52. A hollow conduit 53 is pivotally mounted on sleeve 50 by opposed pins 54 engaging bearings at opposite sides of said conduit near its inner end. The recorder reproducer casing 22 is supported at the outer end of said conduit 53. A rib or fin 55 extends downwardly from conduit 53 with its free edge riding on the upper edge of guide plate 48 to impart up and down rocking movement to said conduit 53 during the longitudinal or to and fro movement thereof which accompanies the adjustment of control lever 27 into and out of its several positions.

As shown in Figure 1, sleeve 50 has a pintle 56 extending across the outer end of slot 45 and in position to be engaged by a terminal hook 57 on a link 58 pivoted at 59 to move with lever 27.

It will be noted that the stylus arm 23 is pivoted at 60 to a bracket carried on the underside of conduit 53 and that the recording stylus 61 and the reproducing stylus 62 are mounted in conventional relation on stylus arm 23.

In apparatus according to my invention, I employ along with the above described conventional or known devices or equivalent operative structure an electric recorder-reproducer or translation unit which, in the illustrated embodiment, is supported in casing 22, Figures 5 and 6, and cooperates with the stylus arm 23 in transmitting vibrations thereto and receiving vibrations therefrom. This unit, in a preferred form known as a bimorph element, comprises a pair of piezo crystal plates 63 and suitable electrodes including a plate 64 of metal foil, for example, connected to a conductor wire 66 and interposed between said crystal plates. An outer metal plate 65 connected to conductor wires 67 is mounted against the outer surface of each of said crystal plates 63. A terminal plate 68 is conveniently located at the inner end of sleeve 50 and provided with binding posts 69.

As shown in Figures 5 and 6, the crystal plates 63 are retained between the opposed walls of the casing 22 by resilient supports, as rubber spacers 70 engaging said plates at three corners. A pin 71 is secured to the free corner of the crystal plates and to an intermediate portion of the stylus arm 23 after passing through an opening 72 in the casing 22, said opening being sealed against passage of moisture by a membrane 73 extending across and covering said opening and closely embracing the shank of pin 71, being preferably adhesively secured thereto. The opening in the

opposite wall of casing 22 and through which the conductor wires are led to the interior thereof, may be substantially sealed to exclude moisture by a thin sheet 74 of suitable moisture resistant material lying against the inner face of said wall 5 and with its edges held down under the annular gasket 75 of rubber or other suitable resilient material. A passage for the conductors 66 and 67 to the interior of the casing may be provided in any suitable way, here shown as through the sealing sheet 74, care being taken to minimize leakage of air into the casing.

As shown in Figure 5, the casing 22 is in effect a shell made up of cooperating shallow cup shaped members one of which is secured to the outer end 15 of hollow conduit 53. The other or outer cup shaped member serves as a cover and when held in position, as by bolts 76, Figure 6, retains the gasket 75 and the crystal plate assembly in operative position inside the casing 22.

For the more effective operation of the translation unit both in recording and reproducing, I employ an amplifier 32, Figure 7, interposed in circuit between said unit and a transmitting and receiving microphone 33, Figure 4, carried in the 25 mouth piece 7. A reversing or change over switch 34 conveniently mounted, as on the frame of the machine, is arranged in said microphone circuit and so connected with the lever 27 that the amplifier will be cut into the circuit in proper relation 30 automatically when the operator moves said control lever 27, and hence the casing 22, to and from recording and reproducing positions respectively. As shown in Figure 2, said switch 34 includes pivoted contact arms 35 with the free ends of each 35 actuated by a rod 36 to move between suitable terminals connected to the circuit and biased in one position by a tension spring 90.

To operate switch 34 automatically by movement of control lever 27, the rod 36 is connected 40 through a link 37 to one arm 38 of a bell crank lever, Figure 4, the other arm of which has a lug 39 positioned in the path of a bail 40 pivotally swung on rod 26. The lower end of a lever 41, pivoted at 42 when moving in one direction engages and moves bail 40 inwardly against lug 39 which swings said arm 38 against resistance of said tension spring 90. Lever 41 is connected to control lever 27 in such a manner that, when the latter is moved to position the recorder reproducer unit and the stylus for recording, bail 40 is thrust inwardly and actuates the arm 38, link 37 and rod 36 to move contact arms 35 clockwise and into engagement with one set of terminals. In the neutral position of control lever 27, and consequently of the stylus, the contact arms 35 are disengaged from the switch terminals.

In operation the electrical impulses generated in the microphone 33 when recording, and in the reproducer unit 22 when transcribing, are amplified by a suitable amplifier 32, as shown in Figure 7, before being transmitted to the recorder unit or to the speaker unit, as the case may be. The amplifier 32 may be of any type capable of supplying sufficient voltage and power output to 65 operate the recorder and the speaker units under all conditions, the same amplifier being used for both recording and reproducing. This double-duty action is accomplished by use of the above described reversing switch 34 to which the amplifier 32 is connected by the input lead 77 and the output lead 78. The switch in turn is connected to the recorder reproducer 22 and the microphone-speaker 33 by the leads 93 and 94 respectively. With this arrangement, either the micro- 75

5 phone or the reproducer may be connected at will to the input terminals of the amplifier 32, and the recorder or speaker to the output terminals thereof respectively, depending upon whether the instrument is to be used as a recorder or as a reproducer.

10 It is to be noted that the amplifier 32, the connecting leads 77 and 78, the switch 34 and the connecting leads 93 and 94 are all shielded (as indicated by the dotted lines) and suitably grounded through the condenser 91 to prevent audio-frequency pick-up between the input and output leads of the amplifier, thereby reducing the likelihood of oscillation or instability in the 15 operation of the instrument. For a similar reason, switch 34 is preferably so designed that its various conducting components have a minimum area and a maximum separation in order to maintain the inter-circuit capacity therebetween at 20 a minimum.

25 The instrument is provided with a switch 31 conveniently mounted on the front of the case, Figure 1, which is normally closed during all times when the apparatus may be expected to be used. The closing of this switch 31 initially energizes the heating elements 79 of the amplifier tubes through the resistor 80 and closes the circuit of the signal light 30 mounted on the front of the instrument case, Figure 1, which then indicates that the 30 switch 31 is closed and that the instrument is connected to the power supply circuit 32.

35 Switch 6, operated from the hook 8 as previously described, includes a stem 81 of insulating material and a metal contact head 82 which, in closed position, engages resilient contacts 83 and 84. When this switch is closed by the removal of the mouth piece 7 from the hook 8, the motor circuit is closed through the contacts 82 and 83. At the same time, the resistor 80 and switch 31 are short-circuited through the contacts 82 and 84, thus 40 permitting full current to pass to the amplifier heater circuit, bringing it up instantaneously to its full operating efficiency. Simultaneously, the intensity of the signal light 30, which is connected across the heating elements 79 of the tubes, increases due to the shorting of the resistor 80, and thereby indicates that the switch 6 is closed and the instrument is in operating condition. With the resistor 80 in the circuit, as by closing 45 of switch 31, the said heating elements 79 of the tubes in amplifier 32 can be maintained in a partially heated condition at all times when the apparatus may be expected to be used. It thus becomes ready for instant use at any moment merely by shorting out this resistor. This arrangement eliminates the need for maintaining the tubes at 50 full operating temperature and subject to full operating potential during those periods when the amplifier is not actually in use, thereby both conserving the life of the tubes and decreasing the power consumption of the device when not in actual operation. However, in case the operator attempts to use the apparatus without having previously closed switch 31, this switch 31 is so 55 connected as to be short-circuited by switch 6 when the mouthpiece 7 is removed from the hook 8, thus placing the apparatus in condition for operation after a period, necessary for heating the tube elements 79, has elapsed.

60 In a typical cycle of operation, switch 31 is closed to initially energize the amplifier filaments as and for the purposes above described. With a record in position on mandrel 2, the operator throws lever 27 to recording position thus simultaneously moving the recording stylus 61 into

6 contact with the record 1 and moving the contact arms 35 of switch 34 against the pull of the spring 90 to connect the microphone 33 to the input of the amplifier 32 and the recorder 22 to the output thereof. The operator then removes 5 the mouthpiece 7 from the hook 8, thus causing the motor 5 to start and preparing the amplifier to function. Button 20 is pressed down to engage the record-turning clutch and the operator speaks into the microphone 33 in mouthpiece 7. The 10 resulting electrical impulses are amplified in the amplifier 32 and transmitted to the recorder 22 and thence to the record 1. To reproduce a portion of the recorded matter the lever 27 is thrown to the reproducing position, thus automatically 15 actuating the change-over switch 34 whereby the recorder is connected as a reproducer and the microphone operates as a speaker when the button 20 is depressed to effect rotation of the record 1.

20 As many embodiments might be made of the above invention, and as many changes might be made in the embodiment above described, it is to be understood that all structure hereinbefore described or shown in the accompanying drawings is to be considered as illustrative only and not in 25 a limiting sense.

I claim:

1. In a dictating machine, the combination of 30 means for supporting and actuating a record element, a recording stylus, a reproducing stylus, 35 means for moving said styli alternatively into operative relation to the record element, a transmitting and receiving microphone, a piezocrystal recorder-reproducer element operatively connected to said styli, and means connected to 40 and cooperating with said stylus moving means and with the microphone whereby in use the microphone operates as a transmitter when the recording stylus is in operative relation to the record element and, alternatively therewith, as 45 a speaker when the reproducing stylus is in operative relation to said record element.

2. In a dictating machine, the combination of 50 means for supporting and actuating a record element, a recording stylus, a reproducing stylus, 55 means for moving said styli alternatively into operative relation to the record element, a transmitting and receiving microphone, a piezocrystal recorder-reproducer element operatively connected to said styli, a circuit including said microphone and said recorder reproducer element, and a change-over switch interposed in 60 said circuit and operatively connected to and actuated by said stylus moving means whereby, in use, the microphone operates as a transmitter when the recording stylus is in operative relation to the record element and, alternately therewith, as a speaker when the reproducing stylus is in operative relation to said record element.

3. In a dictating machine, the combination of 65 means for supporting and actuating a record element, a recording stylus, a reproducing stylus, means for moving said styli alternatively into operative relation to the record element, a transmitting and receiving microphone, a piezocrystal recorder-reproducer element operatively connected to said styli, a circuit including said microphone, said recorder-reproducer element and an amplifier, and a change-over switch 70 interposed in said circuit and operatively connected to and actuated by said stylus moving means whereby, when the recording stylus is in operative relation to the record element, the microphone operates as a transmitter and the impulses so transmitted are impressed in amplified 75

degree on the recorder-reproducer element, and alternatively therewith, when the reproducing stylus is in operative relation to said record element the microphone operates as a speaker and 5 the impulses transmitted thereto from the reproducing stylus and recorder-reproducer element are amplified by said amplifier.

4. In a dictating machine, the combination of means for supporting a record element, means 10 for actuating said record, a recording stylus, a reproducing stylus, means for moving said stylus alternatively into operative relation to the record element, a transmitting and receiving microphone, a piezo-crystal recorder-reproducer element 15 operatively connected to said stylus, a circuit including said microphone, said recorder-reproducer and an amplifier having heater elements in a separate circuit, a change-over switch interposed in said microphone circuit and operatively connected to and actuated by said stylus moving means, and switch means in said heater element circuit and cooperating with said record actuating means for producing a different heating effect in said elements when said record 20 actuating means is in operation from that produced when said record actuating means is not in operation.

5. In a dictating machine, the combination of means for supporting a record element, means 30 for actuating said record, a recording stylus, a reproducing stylus, means for moving said stylus alternatively into operative relation to the record element, a transmitting and receiving microphone, a piezo-crystal recorder-reproducer element 35 operatively connected to said stylus, a circuit including said microphone, said recorder-reproducer and an amplifier having heater elements in a separate circuit, a change-over switch interposed in said microphone circuit and operatively 40 connected to and actuated by said stylus moving means, switch means in said heater element circuit cooperating with said record actuating means for producing a different heating effect in said elements when said record actuating means 45 is in operation, and means for indicating the condition of said heater elements.

6. In a dictating machine, the combination of means for supporting a record element, means for actuating said record, a recording stylus, a reproducing stylus, means for moving said stylus 50 alternatively into operative relation to the record element, a transmitting and receiving microphone, a piezo-crystal recorder-reproducer element operatively connected to said stylus, a circuit including said microphone, said recorder- 55

reproducer and an amplifier having heater elements in a separate circuit, a change-over switch interposed in said microphone circuit and operatively connected to and actuated by said stylus moving means, and switch means connected to 5 and cooperating with said heater element circuit and with said record actuating means whereby the current supplied to said heating elements is increased upon commencement of operation of said record actuating means.

7. In a dictating machine, the combination of means for supporting a record element, means for actuating said record, a recording stylus, a reproducing stylus, means for moving said stylus alternatively into operative relation to the record 15 element, a transmitting and receiving microphone, a piezo-crystal recorder-reproducer element operatively connected to said stylus, a circuit including said microphone, said recorder-reproducer and an amplifier, a change-over 20 switch interposed in said circuit and operatively connected to and actuated by said stylus moving means, and switch means connected to and cooperating with said amplifier circuit and with said record actuating means whereby the voltage applied to said amplifier is increased during the 25 periods when said record actuating means is in operation.

8. In a dictating machine, the combination of means for supporting and actuating a record element, a recording stylus, a reproducing stylus, means for moving said stylus alternatively into operative relation to the record element, a transmitting and receiving microphone, a piezo-crystal recorder-reproducer element operatively 30 connected to said stylus, a circuit including said microphone, said recorder-reproducer element and an amplifier, and a change-over switch interposed in said circuit, said switch comprising 35 two relatively widely spaced parallel conductive 40 arms operatively connected to and actuated by said stylus moving means, each of said arms being pivoted at one end and having its free end adapted to move between and to contact two of three spaced contacts whereby, when the recording stylus is in operative relation to the record 45 element, the microphone is connected through said amplifier to said recorder-reproducer element to operate as a transmitter, and alternatively therewith, when the reproducing stylus is 50 in operative relation to said record element, the microphone is connected through said amplifier to said recorder-reproducer element to operate as a speaker.

LELAND D. NORTON. 55
